CONTAINER

William M. Brockenbrough and Harry S. Norris,
Savannah, Ga., assignors to Evans Products
Company, a corporation of Delaware

Application September 14, 1934, Serial No. 743,947

8 Claims. (Cl. 217—89)

The invention relates to containers particularly adapted for shipping agricultural products or the like.

One object of the invention is to provide an improved container construction which is inexpensive to manufacture and which has increased strength and rigidity so as to provide greater resistance to breakage or distortion of the container during shipment.

Another object of the invention is to provide an improved container construction which has improved means for retaining the heads in the ends of the container.

Another object of the invention is to provide improved means for retaining the heads in the ends of the container which enables an efficient assembly of the heads and the side wall of the container while still permitting a quick removal of the head and replacement thereof whenever necessary.

Another object of the invention is to provide an improved means for connecting the ends of metal bands encircling the side wall of a container.

For a better understanding of the invention reference may be had to the accompanying drawing forming a part of the specification, wherein:

Figure 1 is an elevational view illustrating a container constructed according to one form of the invention.

Fig. 2 is a cross-sectional view on a larger scale taken substantially along the line 2—2 of Fig. 1.

Fig. 3 is a cross-sectional view on a larger scale taken substantially along the line 3—3 of Fig. 1.

Fig. 4 is a cross-sectional view on a larger scale taken substantially along the line 4—4 of Fig. 1.

Fig. 5 is a fragmentary, elevational view of a container constructed according to another form of the invention.

Fig. 6 is a cross-sectional view on a larger scale taken substantially along the line 6—6 of Fig. 5.

Fig. 7 is a detail view illustrating an improved means for connecting the ends of the metal bands as constructed according to another form of the invention.

Referring to Fig. 1, the container illustrated comprises a side wall formed by a series of spaced wooden slats 10 encircled at opposite ends by metal bands 11 and 12. Each band is connected to the ends of the slats by means of projections on the band which project into the slats and the particular means shown for this purpose is disclosed in Patent No. 1,907,022, issued May 2nd, 1933. The ends of the container are closed normally by means of heads 13 and preferably each

head comprises two layers 14 and 15 having their grains disposed in crossed relation. As shown by Fig. 4, the inner layer 15 of the head is of smaller diameter than the layer 14 and is disposed within the slats while the outer layer 14 rests on the ends 5 of the slats. This construction is desirable in that engagement of the inner layer with the inner surfaces of the slats provides a transverse rigidity which increases the strength and resistance to lateral distortion of the container. 10

At the end of each slat, each of the bands 11 and 12 has a struck-out tab 16 which is bent over the end of the slat in embracing relation thereto and this feature in combination with the struck-out projections extending into the slats 15 provides a very positive connection between the bands and the slats. Between the tabs 16 and circumferentially between the slats, each band is provided with tabs 17 that are bent over the outer surface of the head after the latter is inserted. It will therefore be observed that the outer layer 14 of the head is held between the tabs 16 and 17 and that since the tab 16 is bent over the ends of the slats, the layer 14 is supported also and indirectly by the ends of the slats. Removal 20 of the head may readily be accomplished by reversely bending a sufficient number of the tabs 17 to permit withdrawal of the head laterally or else the entire number of tabs may be reversely bent. This means for holding the head in place 20 readily permits removal and replacement of the head when inspection of the contents of the container is required. It will be noted that the ends of the band overlap each other and that a fragment of one of the tabs 17 is provided at the end 30 of each band so that such fragments together 35 provide a tab corresponding to the others.

For connecting the ends of the bands, one end of the band is provided with struck-out tabs 20 adapted to project through spaced slots in the other end and after the ends are overlapped and the tabs are inserted through the slots, the tabs are bent over so as to lock the ends together. 40

The construction shown by Figs. 5 and 6 is similar to that shown by Fig. 1 with the exception that the tabs 16 are eliminated. In this construction the head 13 rests directly on the ends of the slats and the same type of head as shown by Fig. 4 may be employed so that the layer 14 rests on the ends of the slats while the 50 layer 15 is disposed within the slats. In the construction shown, however, both layers are of the same diameter and the marginal portion of the band projecting beyond the ends of the slats is slightly wider so as to cover the edge of both 55 layers 14 and 15.

In the construction shown by Fig. 7 each end of the band has oppositely disposed tabs and after disposing the ends in overlapping relation, the tabs on both ends are bent over in the same direction so that the tabs on one end embrace the tabs on the other end. In this arrangement, bending over of the inner tabs requires that the outer tabs bend in a wider arc in embracing the inner tabs, thereby avoiding a sharp bend which might cause cracking or splitting of the outer tab at the line of bending. This connection is much stronger and durable than in the case where the inner tabs are eliminated.

In constructing the container it will be appreciated that the bands are formed with the tabs and projections and assembled with the slots in a machine adapted for this purpose. Then the blank thus provided is bent into cylindrical shape and the ends of the bands are connected, following which the head is inserted at one end of the container and after disposing the products to be shipped in the container, the head at the other end of the container is inserted. Inspection of the container may be readily accomplished by removing one of the heads and the head may be easily re-inserted as previously described. The invention provides a very strong and rigid container having great resistance to lateral distortion as well as distortion longitudinally of the container and the connections between the bands and the slats provides a very positive and strong means for holding these parts assembled. Furthermore, the invention provides an efficient as well as an inexpensive means for positively connecting the ends of the bands while still enabling a quick assembly.

While more than one form of the invention has been illustrated and described in detail, it will be apparent to those skilled in the art that various modifications may be made without departing from the scope of the appended claims.

We claim:

1. A container comprising a side wall, a metal band around the end of the side wall at the outer side of the latter, and a head over the end of the side wall, said band having circumferentially spaced portions bent inwardly over the end of the side wall and portions between the first portions which are releasably bent over the outer side of the head for removably fastening the head relative to the end of the side wall.

2. A container comprising a side wall, a metal band around the end of the side wall, a head over the end of the side wall, and means retaining the head in place, said means comprising circumferentially separated and inwardly bent portions of the band certain of which overlap the inner side of the head and others releasably engage the outer side of the head for removably fastening the same relative to the end of the side wall.

3. A container comprising a side wall, a metal

band encircling the side wall at one end thereof, a head for the end of the container, and means comprising struck out portions on the band for engaging and holding the head releasably against movement either inwardly or outwardly with respect to the side wall.

4. In a container, a side wall, a metal band encircling the side wall, and means holding the ends of the band together and in overlapping relation, said means comprising tabs at opposite edges of the ends of the band which are bent transversely of the band in the same direction so that at each edge one tab embraces the other tab in a manner so as to prevent relative lateral disengagement thereof.

5. A container comprising a side wall of spaced slats, a metal band around the ends of the slats at the outer side of the latter, a head on the ends of the slats, means comprising struck out tongues on the inner edge of the band projecting into the slats for securing the band to the latter, and struck out tabs on the opposite edge of the band and between the slat securing tongues which are bent over the head for retaining the latter in place.

6. In a container, a side wall, a metal band encircling the side wall, and means holding the ends of the band together and in overlapping relation, said means comprising laterally aligned tabs on the edges of the overlapping ends of the band and formed by laterally directed slits, wherein tabs on opposite ends of the band are bent over in the same direction with one on one end of the band bent over between the slits in the other end of the band and into an embracing relation with the tab on said other end of the band.

7. A container comprising, a side wall, a metal band having a portion of its width engaging the outer face of and at the end of said side wall and the other portion transversely slit at longitudinally spaced distances, alternate portions of the band between said slits being bent inwardly over and down the inner face of the side wall and terminating in uniplanar inwardly directed flanges, a head resting on the upper faces of said flanges, and the remaining portions of the band between the slits being bent to releasably engage the upper face of said head.

8. In a container, a side wall, a metal band encircling the side wall, and means holding the ends of the band together and in overlapping relation, said means comprising tabs at opposite edges of the ends of the band which are bent transversely of the band in the same direction to form a nested relation therebetween, and means including one of the tabs for preventing longitudinal displacement of said ends.
